(57) **CLAIM**

The ornamental design for a trailer, as shown and described.

DESCRIPTION

FIG. 1 is a perspective view of a trailer from one side, with the top of the trailer and the rear doors in the closed position; FIG. 2 is a perspective view of a trailer from one rear corner, with the top of the trailer and the rear doors in the closed position;

FIG. 3 is a perspective view of a trailer from the front, with the top of the trailer and the rear doors in the closed position;

FIG. 4 is a perspective view of a trailer from above, with the top of the trailer and the rear doors in the closed position;

FIG. 5 is a perspective view of a trailer from the front, with the top of the trailer and the rear doors in the open position;

FIG. 6 is a perspective view of a trailer from the same side as in FIG. 1 side, with the top of the trailer in the open position and the rear doors in the closed position;

FIG. 7 is a perspective view of a trailer from the rear, with the top of the trailer in the open position and the rear doors in the closed position;

FIG. 8 is a perspective view of a trailer from the rear, with the top of the trailer in the open position, one of the rear doors in the closed position, and one of the rear doors in the closed position;

FIG. 9 is a perspective view of a trailer from the rear, with the top of the trailer and both rear doors in the open position; and, FIG. 10 is a perspective view of a trailer from one rear corner, with the top of the trailer and both rear doors in the open position, the trailer including an awning suspended from the top of the trailer.

In the drawings, the broken lines depict portions of the article that form no part of the claim.
